UNITED STATES PATENT OFFICE

WILLEM VAN RIJSWIJK, OF ENNETBADEN, SWITZERLAND

LABYRINTH GLAND FOR MACHINE SHAFTS

Application filed April 6, 1927, Serial No. 181,595, and in Germany April 15, 1926.

This invention relates to sealing glands for leading out operating shafts from machines handling gases at a superatmospheric pressure.

5 The general object of the invention is the provision of a simple gland construction which will be effective to prevent loss of gases from the machine about the shaft and to reduce the actual flow of fluid through the 10 gland.

Another object is the provision of an arrangement whereby the desired pressures may be maintained automatically within different portions of the gland for the purpose of 15 preventing leakage and escape of gases through the same.

Other and incidental objects will be pointed out or indicated hereinafter or will appear to one skilled in the art upon an understanding 20 of the invention or its employment in practice.

In the drawing forming a part of this specification, I illustrate three arrangements of structure representative of some embodiments of the invention, the same being shown 25 in diagrammatic fashion. It is to be understood, however, that these are presented for illustrative purpose and are not to be construed in any fashion to have the effect of 30 limiting the claims to these particular arrangements or short of the true and most comprehensive scope of the invention in the art.

In said drawing, 35 Fig. 1 is a diagrammatic illustration in the nature of a longitudinal section through a gland, showing a part of the operating shaft with which it cooperates and a portion of the machine casing served by the gland 40 and the shaft;

Fig. 2 is a similar section, diagrammatically illustrated, of a modified arrangement of apparatus; and

45 Fig. 3 is a similar diagrammatic illustration of a third form.

The present invention relates to a type of gland which is adapted to accomplish its sealing action without the use of a liquid sealing medium. Certain advantages are to be attained by an effective gland of this type, as

it precludes the possibility of the absorption of an external sealing medium by the working fluid within the machine. By virtue of the present invention, there is accomplished a gradual reduction of the pressure of working 55 fluid which may be working out along the shaft, so that its escaping tendency is overcome, the greater proportion of the working fluid being returned to the machine or system and all of the remainder being properly controlled and directed to a proper point of disposal for recovery or for discharge at a point where it will occasion no inconvenience or harm.

A more detailed understanding of the invention may be obtained by consideration of the illustrative arrangements shown in the drawing. In the arrangement illustrated in Fig. 1, the reference numeral 10 designates a portion of the machine casing, and all of the remainder being properly controlled and directed to a proper point of disposal for recovery or for discharge at a point where it will occasion no inconvenience or harm.

Another object is the provision of an arrangement whereby the desired pressures may be maintained automatically within different portions of the gland for the purpose of preventing leakage and escape of gases through the same.

Other and incidental objects will be pointed out or indicated hereinafter or will appear to one skilled in the art upon an understanding of the invention or its employment in practice.

In the drawing forming a part of this specification, I illustrate three arrangements of structure representative of some embodiments of the invention, the same being shown in diagrammatic fashion. It is to be understood, however, that these are presented for illustrative purpose and are not to be construed in any fashion to have the effect of limiting the claims to these particular arrangements or short of the true and most comprehensive scope of the invention in the art.

In said drawing, 35 Fig. 1 is a diagrammatic illustration in the nature of a longitudinal section through a gland, showing a part of the operating shaft with which it cooperates and a portion of the machine casing served by the gland 40 and the shaft;

Fig. 2 is a similar section, diagrammatically illustrated, of a modified arrangement of apparatus; and

45 Fig. 3 is a similar diagrammatic illustration of a third form.

The present invention relates to a type of gland which is adapted to accomplish its sealing action without the use of a liquid sealing medium. Certain advantages are to be attained by an effective gland of this type, as

mospheric pressure due to the fluid finding access thereto from the high pressure end of machine casing 10 through the operating clearance between the shaft and the gland.

5 By the pressure regulator 22 the pressure in the recovery tapping 17 is maintained at a point only slightly above atmospheric, but below the pressure in reducing tapping 14. When the pressure in the recovery tapping 10 17 tends to exceed the maximum, the pressure regulator 22 opens its valve and admits pressure fluid to the ejector 20 to draw fluid from the tapping 17 and raises it to the pressure in pipe 16 so that it may be returned to the operating chamber of the machine. Consequently, if the pressure at the point where pipe 16 is connected to the machine chamber is considerably higher than atmospheric pressure so that there is a tendency for leakage from 20 the reducing tapping 14, the greater portion of the fluid reaching the recovery tapping 17 is returned. It follows, therefore, that the pressure of the escaping fluid is reduced at the reducing tapping 14 to that existing in the 25 low pressure portion of the machine chamber, and the pressure of fluid leaking from the chamber 14 through the operating clearance is further reduced in the recovery tapping 17 to a point only slightly in excess of atmospheric pressure. The further leakage from the recovery tapping 17, consequently, will be very slight, so that there will be very little loss from the machine. In order that this small residual leakage may be recovered 30 or may be conveyed to a point of disposal where it will occasion no harm or inconvenience, the exhaust tapping 18 is provided with a pipe 24 through which the fluid is conveyed to a suitable point of disposal, the fluid being 40 drawn off through said pipe by suction which maintains the exhaust tapping 18 at sub-atmospheric pressure. The pressure in exhaust tapping 18 is controlled by a pressure regulator 25 which opens a valve in pipe 24 to render the suction effective whenever the pressure in pipe 24 and tapping 18 reaches a predetermined maximum.

In the arrangement illustrated in Fig. 2, the parts correspond to those shown in Fig. 1, 50 with the exception that a compressor 26 is employed in place of the ejector 20, said compressor being operated by gearing connections 27 with the shaft 11.

In the arrangement illustrated in Fig. 3, 55 the organization is as described with reference to Fig. 1, with the addition of an impeller 28, carried by shaft 11 for discharging fluid from the exhaust tapping 18 to the exhaust pipe 24' whereby it is led to a suitable absorption or recovery device 29. It 60 will be understood that the absorption or recovery device may be utilized also in connection with the arrangements illustrated in Figs. 1 and 2. In the arrangement illustrated in Fig. 3, the fluid finding access to

exhaust tapping 18 from the recovery tapping 17, as well as air drawn in from outside the gland, are compressed at the periphery of the impeller to a degree sufficient to overcome the frictional resistance in the exhaust 70 pipe. In this case, the pressure in the recovery tapping 17 must be maintained slightly above the final pressure of the impeller 28, and this may be accomplished automatically through the medium of the pressure regulator 22 which operates at a selected differential 75 between the pressure in recovery tapping 17 and the final impeller pressure in exhaust tapping 18.

It is believed that the operation of the several devices is clear from the foregoing description without further detailed repetition, and that from the same it is apparent that leakage through the gland is definitely controlled and that all fluid tending to escape 80 through the gland is either returned to the machine or disposed of in a selected and definitely controlled fashion.

What I claim is:

1. In a sealing gland for machine casings 90 having a member extending therefrom, a gland structure associated with the casing about the member and having a plurality of chambers formed therein, a conduit connecting two of the chambers to a space at super-atmospheric pressure, a conduit connecting another of the chambers to a space at sub-atmospheric pressure, and a pressure-operated valve for automatically maintaining substantially atmospheric pressure in one of 95 the two chambers connected to the space at super-atmospheric pressure.

2. In a sealing gland for machine casings having a member extending therefrom, a gland structure associated with the casing about the member and having a plurality of chambers formed therein, one of said chambers being arranged to receive a fluid from a space of high pressure in said casing, a 100 conduit connecting the said one of said chambers with a second of said chambers and with a space at super-atmospheric pressure lower than the pressure in the said space of high pressure, a conduit connecting a third chamber to a space at sub-atmospheric pressure, means in the conduit connecting the first and second chambers operative to cause 105 flow of fluid from the said second chamber to the said space at super-atmospheric pressure by way of the first said conduit, the said means being connected with the said space of high pressure, and a valve controlled by pressure in the second chamber operative to cause 110 the pressure in the said second chamber to be maintained at substantially atmospheric pressure.

3. In a sealing gland for machine casings 115 having a member extending therethrough, a gland structure associated with the casing 120 having a plurality of chambers formed therein, a conduit connecting two of the chambers to a space at super-atmospheric pressure, a conduit connecting another of the chambers to a space at sub-atmospheric pressure, means in the conduit connecting the first and second chambers operative to cause flow of fluid from the said second chamber to the said space at super-atmospheric pressure by way of the first said conduit, the said means being connected with the said space of high pressure, and a valve controlled by pressure in the second chamber operative to cause 125 the pressure in the said second chamber to be maintained at substantially atmospheric pressure.

4. In a sealing gland for machine casings 130 having a member extending therethrough, a gland structure associated with the casing

about the member and having a plurality of chambers formed therein, one of said chambers being arranged to receive a fluid from a space of high pressure in said casing, a conduit connecting the said one of said chambers with a second of said chambers and with a space at super-atmospheric pressure lower than the pressure in the said space of high pressure, a conduit connecting a third chamber to a space at sub-atmospheric pressure, 10 an ejector in the conduit connecting the said first and second chambers operative to cause flow of fluid from the second of said chambers to the said space at super-atmospheric 15 pressure by way of the first said conduit, the said ejector being connected with the said space of high pressure, and a valve controlled by pressure in the second chamber operative to control operation of the said ejector to cause flow of fluid from the second chamber 20 at such rates as to maintain the pressure therein at substantially atmospheric pressure.

In testimony whereof I have hereunto subscribed my name this 17 day of March, A. D., 25 1927, at Zurich, Switzerland.

WILLEM VAN RIJSWIJK.
